UNITED STATES PATENT OFFICE.

CHARLES F. ELMORE, OF CHICAGO, ILLINOIS.

WATCH-HOLDER.

1,116,808.

Specification of Letters Patent. Patented Nov. 10, 1914.

Application filed March 3, 1914. Serial No. 822,122.

To all whom it may concern:

Be it known that I, CHARLES F. ELMORE, a citizen of the United States, residing at Chicago, in the county of Cook and State 5 of Illinois, have invented a new and useful Improvement in Watch-Holders, of which the following is a specification.

My invention relates to certain new and useful improvements in watch holders and 10 is fully described and explained in the specification and shown in the accompanying drawings, in which:

Figure 1 is an elevation of a bracelet including my improved device; Fig. 2 is a 15 view of the holder proper from the left of Fig. 1; Fig. 3 is a similar view looking in the opposite direction; Fig. 4 is a view of the watch-holder, similar to Fig. 2, but with the watch removed; Fig. 5 is a section 20 through the clasp which holds the watch-holder in closed position, and Fig. 6 is a section through the bracelet clasp.

Referring to the drawings, 7 is the watch to be held by my improved device, 8 indicating 25 its ring and 9 its stem. 10 and 11 are two substantially semi-circular parts which are provided with ears pivoted together upon a pin 12. Each of the parts 10 and 11 is in the form of an inwardly-faced slightly 30 channeled section adapted to embrace the periphery of the watch, as illustrated. The parts 10 and 11 have at their free ends outwardly-extending loops 13, the upper ends of which loops are approximately in the 35 medial planes of the parts 10 and 11 and the lower ends of which are to one side of that plane, as shown in Fig. 1, the openings through the loops being thus inclined or angularly disposed with reference to the 40 plane of the watch. When the parts 10 and 11 are clasped together upon the watch which they hold, the ring 8 of the watch being turned toward the back thereof, these loops slide over the ring from opposite sides, 45 so as to hold the same in the manner shown in Figs. 1, 2 and 3. The loops are, however, low enough to leave the stem free to be manipulated in the usual manner.

For the purpose of holding the parts 50 firmly in position upon the watch which is to be held thereby, the loops are provided with means for engaging them with each other. This means may be of any desired form, that shown in the drawings consisting 55 of a female part 14 on one loop and an elastic male part on the other loop. When the

parts are swung together to clasp the watch, the male part 15 enters the female part 14 and expands to engage a shoulder 16 from which it may be disengaged, when desired, 60 by passing a small instrument, such as a common pin, through a hole 17 in the female part 14.

While the holder herein shown may be used in various connections, it is especially 65 designed for use as a part of a bracelet, such as that illustrated. To that end, the pivot pin 12 is provided with a transverse pivot 18 and the loop 13, on one of the parts, carries a similar pivot 19 to which are secured 70 the sections of the bracelet. These bracelet sections are shown as separable and engaged with each other by a clasp 20 of common construction, such as is shown in Fig. 6.

There is thus provided a device which 75 firmly holds a watch, which is as light as is consistent with accomplishing its purpose, which leaves both faces thereof exposed and which makes adequate disposition 80 for engaging the ring of the watch in a position as little conspicuous as is possible. The stem is left so disposed as that it may readily be manipulated, and the structure is, therefore, very satisfactory. It may be 85 placed in position upon a watch with greatest ease and may be removed almost instantly therefrom.

I realize that considerable variation is 90 possible in the details of the construction herein shown, and I do not intend to limit myself thereto, except as pointed out in the following claims, in which it is my intention to claim all the novelty inherent in the device as broadly as is permitted by the state 95 of the art.

What I claim as new and desire to secure by Letters Patent is:—

1. A watch-holder comprising pivoted sections, each of semi-circular form inwardly-channeled in cross-section to receive and hold the periphery of a watch with both its faces free, loops at the free ends of the sections to fit over the ring of the watch when turned back, and means for holding 105 said sections together.

2. A watch-holder comprising pivoted sections, each of generally semi-circular form and inwardly channeled to coöperate with the periphery of a watch to hold the 110 same, leaving its two faces exposed, loops at the free ends of said sections to receive

and hold the ring of a watch, and means for holding said loops in engagement with each other.

3. A watch-holder comprising pivoted sections, each of generally semi-circular form and inwardly channeled to coöperate with the periphery of a watch to hold the same, leaving its two faces exposed, loops at the free ends of said sections to receive and hold the ring of a watch, and a male part on one loop and a female part on the other to receive the male part, said male and female parts coöperating to lock the sections together.

4. In combination two pivoted sections, each generally semi-circular in form and inwardly channeled to receive the periphery of a watch and hold the same between them with both its faces exposed, loops at the free ends of said sections to receive the ring of the watch, engaging means on the loops

for holding them together to lock the sections in position, and a bracelet connected to the sections, for the purpose set forth.

5. In combination two pivoted sections, each generally semi-circular in form and inwardly channeled to receive the periphery of a watch and hold the same between them with both its faces exposed, loops at the free ends of said sections to receive the ring of the watch, engaging means on the loops for holding them together to lock the sections in position, and a bracelet connected to the pivot and loops respectively, for the purpose set forth.

In testimony whereof I have hereunto set my hand this 26th day of February, 1914.

CHARLES F. ELMORE.
